UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

SHUTTLE-FEELER THREAD CUTTER.

Application filed January 17, 1925. Serial No. 3,051.

To all whom it may concern:

Be it known that I, ALONZO E. RHOADES, a citizen of the United States, residing at Hopedale, in the county of Worcester and State of Massachusetts, have invented an Improvement in Shuttle-Feeler Thread Cutters, of which the following description, in connection with the accompanying drawings, is a specification, like characters on the drawings representing like parts.

This invention relates to shuttle feeler thread parters or cutters whereby the spent filling between the cloth selvage and shuttle is parted when filling replenishment is to be effected.

As now ordinarily constructed, shuttle feeler thread cutters are mounted upon the shuttle feeler and move with it to its rearward shuttle feeling position, one of the parters being fixed to the shuttle feeler and the other being actuated by lay movement to sever or part the filling as the lay moves toward its front position.

The present invention differs from such shuttle feeler thread parters in that the present invention provides two parting members each of which is supported upon the shuttle feeler for movement relative thereto to part the filling thread. In carrying the invention into practical effect, one of the parting members or blades is shown as pivotally supported upon the shuttle feeler and provided with a heel to be struck by the lay as the latter moves frontwardly to give to the parter or blade its parting movement, and associated with such parting member or blade is another parting member or blade also mounted on the feeler for movement in the performance of its cutting or parting function. In effecting movement of the two parting members or blades simultaneously to cut or part the thread, one of them is actuated at the proper time, and preferably by lay movement, and connections are provided between the two parting members or blades such that when the lay operated parter or blade is actuated, the other parter or blade will be simultaneously actuated, so that the filling thread will be cut or parted by the combined action of the two parting members or blades.

It is now the usual practice to provide the shuttle feeler with some kind of a clamp, to clamp the end of the filling thread leading to the cloth selvage and to carry the end

frontwardly in order that the portion of such end adjacent the cloth selvage shall be properly presented to the temple thread cutter. In prior constructions it has been the usual practice to form the clamp as a part fixed to the shuttle feeler and sometimes to clamp the end of the thread between such stationary clamping member and a movable thread parter or blade. In accordance with the present invention, the clamping member is mounted on the shuttle feeler for movement relatively thereto to clamp the end of the thread leading to the cloth selvage between itself and one of the thread parters or blades. Such movement of the clamping member gives an increased hold on the end of the thread and prevents its being withdrawn from the clamp as the shuttle feeler moves to front position.

The invention and new combination of parts will best be made clear from the following description and the accompanying drawings of one good form thereof.

In the drawings:

Fig. 1 is a side elevation of a shuttle feeler provided with the present invention, some of the loom parts being omitted;

Fig. 2 is a detail of the thread parter showing the two members thereof as having been moved to cut or part the thread;

Fig. 3 is a top view partly in section showing the pin and slot connection between the two members of the parter and between one of the members of the parter and the clamp;

Fig. 4 is an enlarged front detail showing the position of the parts after the cutting operation.

The loom frame 1 may be of any usual or desired character and, as shown, has connected thereto a bracket 1 on which is pivotally mounted at 2 the shuttle feeler 3, the rearwardly extending end portion 4 of which is provided with an opening 5, as usual. Extending from the shuttle feeler is a lug 6 or pin which is engaged by the jaws 7, 8 which are actuated from an indicating mechanism, (not shown) for moving the shuttle feeler to its rearward shuttle feeling position when an indication has been made for replenishment of filling or other change in the loom operation.

The shuttle feeler is shown in the present instance as being guided in its movement towards and from the front of the loom by a

guide 9 but this may not always be necessary.

Mounted on the shuttle feeler are the two movable parting members or cutting blades which are so associated that upon movement 5 of one blade to part or cut the filling, movement of the other blade will also be effected.

In the present instance of the invention, one of the parting members or blades 10 is pivotally mounted on a stud 11 extending 10 from the shuttle feeler, and for identification the parter or blade 10 will be designated the "primary" parter member.

Extending downwardly from the front end portion of the primary parter member 15 10 is the heel 12 which is adapted to be struck by the lay as it moves towards front position to actuate the parter members to part or cut the thread. In the present instance of the invention the lay 13 has a striking member or bunter 14 mounted thereon, which is adapted to engage the heel 12 when the shuttle feeler is in its rearward shuttle feeling position and the parting members are open, as shown, to thereby effect movement 20 of the parting members in their parting or cutting operation. If desired, the primary parting member 10 may have a cutting edge 15.

Mounted upon the shuttle feeler 3 is the 30 thread parter or blade 16 which may for identification be known as the "secondary" parter member, and is here shown as provided with a large opening 17 through which passes the bolt 11 on which bolt the primary parter member is pivotally mounted. The secondary parter member 16 has a cutting edge 18 and is pivotally supported on a pin 19 extending laterally from the shuttle feeler 3 and passing through an opening 20 formed in the primary parter member. The enlarged opening 17 which is formed in the secondary parter member 16 permits movement 40 of the secondary parter member about its pivotal support 19, and yet affords means for limiting such movement.

In accordance with the present invention, the two parter members 10 and 16 are to be moved relative to the shuttle feeler in the performance of their parting function, and 50 as one means for effecting movement of the secondary parter member by movement of the primary parter member, the latter is here shown as provided with a pin 21 extending laterally thereof and engaging a recess or opening 22 formed in the secondary parter member. The recess 22 in the secondary parter member is formed on a curve 55 which is eccentric to the pivotal axis of the primary parter member 10 or pin 11, the result being that when the primary parter member is actuated by lay movement from the position indicated in Fig. 1 to that of Fig. 2, the pin 21 riding in the eccentric slot 60 22 will effect simultaneous movement of the secondary parter member, so that both

parter members will partake of the movement in their cutting function. In Fig. 1 the line *a* indicates a circular path concentric to the axis of the primary parter member 10 and it will be noted that the slot 70 22 is eccentric thereto.

In some cases it may be desirable to provide a clamp for holding or clamping the end of the filling thread leading to the cloth selvage, and as shown herein, such clamp 75 may be formed by a clamping member 23 preferably mounted on the shuttle feeler at the side of the primary parting member 10, as indicated in Fig. 3. The clamping member 23 has an end portion 24 between which 80 and the side of the primary parter member 10 the thread *b* may be clamped, as indicated in Fig. 4. In the present instance the clamping member 23 is provided with the bifurcated end portion 25 which embraces the pin 19 on which the secondary parter member is pivoted, and the clamping member is provided with an opening 26 similar to the opening 22 formed in the secondary parter member and arranged eccentrically to the 85 pivotal support of the primary parter member 10. Extending laterally from the primary parter member 10 is the pin 27, Fig. 3, which engages the eccentric opening 26 in the clamping member, and the clamping member 23 is also provided with an enlarged opening 90 similar to the opening 17 formed in the secondary parter member and embracing the stud or pin 11, the construction being such that upon actuation of the primary parter member by lay movement, both the secondary parter member and the clamping member will be moved about their pivotal supports to cooperate with the primary parter member to part the thread and clamp 100 it between the primary parter member and the clamping member 23, as indicated in Fig. 4.

The bolt 11 on which the primary parter member 10 is pivoted and which also passes through the enlarged opening 17 of the secondary parter member and a similar opening in the clamping member 23, may be provided with a spring washer 28, as indicated in Fig. 3, for holding the parts in their assembled relation, as indicated. As shown, the primary parter member 10 is disposed between the secondary parter member 16 and the clamping member 23, but in accordance with the present invention, this particular relation of parts may not always be necessary.

From the construction described as a good practical form of the present invention, it will be noted that the thread parter comprises two parter members or blades mounted upon the shuttle feeler for movement relatively thereto in the performance of the thread parting and cutting function, and that, as shown, such movement of the two

parter members or blades is effected by connections between the two which transmit movement of one of the parter members or blades to the other parter member or blade. 5 As shown, also, the invention further comprises a clamping member which is moved during the operation of the parting members to clamp the end of the filling between one of the parting members and the movable clamp. 10 The heel 12 of the primary parter member 10 is provided with a pin 29 whereby the primary parter member may be moved to its open position as the shuttle feeler is moved to its rearward shuttle feeling position, and, of course, simultaneously, the secondary parter member will be moved to its open position. Any suitable means may be employed for opening the members of the 15 parter as the shuttle feeler moves to rearward position, but in the present instance of the invention, the bracket 1 has secured thereto at 30 the upstanding trip arm 31 on which is pivotally supported at 32 the trip 20 33 which may be of usual construction and adapted to operate upon the pin 29 of the primary member, as the shuttle feeler moves to rearward position to open the parter members as the pin 29 rides along the inclined surface 34 of the trip. When the 25 two movable parter members have been closed upon each other to part the thread and the shuttle feeler is moved to its front position, the pin 29 will ride under the trip 30 33, lift the same, and then pass frontwardly thereof, the parter members still remaining closed and the clamping member still remaining in its holding or clamping relation with one of the parter members. As the 35 shuttle feeler moves to its rearward feeling position, the pin 29 will effect opening movement of the parting members and also of the clamp. The trip 33, as shown, has a stop 35 which is adapted to engage a stop 40 36 on the upstanding arm 31 to limit backward swinging movement of the trip.

What is claimed is:

1. In a loom, the combination of a shuttle feeler, a thread parter mounted on the shuttle feeler to part the outgoing filling between the shuttle and cloth selvage and comprising a pivoted primary parter member adapted to be pivotally operated by frontward movement of the lay, a secondary parter member independently pivoted on the shuttle feeler, and eccentric connections between said parter members for causing pivotal thread parting movement of the primary member to effect thread parting movement to the secondary member. 50 55 60

2. In a loom, the combination of a shuttle feeler, a thread parter mounted on the shuttle feeler and comprising two members independently pivoted on the shuttle feeler to turn about separate axes, and connections 65

between the two members of the parter for causing pivotal closing and opening movement of one of them to impart similar pivotal movements to the other. 70

3. In a loom, the combination of a shuttle feeler, a thread parter comprising two members independently pivoted on the shuttle feeler to turn about separated axes, and means for causing each of said members to pivotally move towards the other to part 75 the thread. 80

4. In a loom, the combination of a shuttle feeler having two movable thread parting blades which are pivoted independently on the shuttle feeler at points different distances from the end of the feeler, and connection between the blades for causing thread parting pivotal movement of one blade to effect thread parting pivotal movement of the other blade. 85

5. A shuttle feeler, a thread parting blade pivotally mounted on the feeler, a second thread parting blade pivotally mounted on the feeler at a point frontward of the pivot, and means for causing thread parting 90 pivotal movement of one blade to cause thread parting pivotal movement to the other blade to part the thread between them. 95

6. In a loom, the combination of a shuttle feeler, a thread parter and clamp mounted on the shuttle feeler comprising two blades pivoted on different horizontal axes and pivotally movable towards each other to part the thread a pin carried by one of the blades and an eccentric slot in the other blade engaged by said pin and a thread clamp movable with one of said blades for clamping the thread. 100

7. In a loom, the combination of a shuttle feeler, an upper cutting blade and a lower cutting blade both of which are pivotally mounted on the shuttle feeler and one of which is adapted to be moved on its pivot by the lay, and connections between the blades 105 110 for causing the pivotal movement of the lay operated blade to impart pivotal thread cutting movement to the other blade said connections comprising a pin fixed to one of the blades and an eccentric slot formed 115 in the other blade engaged by said pin. 120

8. In a loom, the combination of a shuttle feeler, a thread parting blade pivotally mounted on the feeler and adapted to be pivotally operated by the lay movement, a second thread parting blade independently pivoted on the feeler at a point frontward of the pivot of the first parting blade, and connections between the blades to cause both blades to be pivotally operated to cut 125 the thread. 130

9. In a loom, the combination of a shuttle feeler, a thread parting blade pivotally mounted on the shuttle feeler to part a thread and having a pin fixed thereto, a 130

- 4
- second thread parting blade pivotally mounted on the shuttle feeler and having a slot which is engaged by the pin fixed to the other blade, for causing pivotal thread parting movement of one of the blades to impart thread parting movement to the other.
- 5 10. A shuttle feeler thread cutter, comprising in combination, two thread parting members pivotally mounted on the shuttle feeler for movement about independent centres at different distances from the shuttle engaging end of the feeler, and connections between the two members for causing 15 both of them to pivotally close simultaneously upon and to part the thread.

11. In a loom, the combination of a shuttle feeler, a thread parter mounted on the shuttle feeler and comprising two pivoted members, one of which has a pin fixed thereto and the other of which has a slot engaged by the pin for causing pivotal closing and opening movement of one of them to impart similar pivotal movements to the other, and a thread clamp movable with one 20 of the parting members to clamp the thread between itself and the other parting member.

25 In testimony whereof, I have signed my name to this specification.

ALONZO E. RHOADES.
